UNITED STATES PATENT OFFICE.

THOMAS BENFIELD, OF NEWARK, NEW JERSEY.

DESIGN FOR A WATCH-CASE.

SPECIFICATION forming part of Design No. 19,634, dated February 4, 1890.

Application filed December 24, 1889. Serial No. 334,882. Term of patent 14 years.

To all whom it may concern:

Be it known that I, THOMAS BENFIELD, residing at Newark, in the county of Essex and State of New Jersey, a subject of the Queen of Great Britain, have invented and produced a new and original design for Watch-Cases, of which the following is a specification, reference being had to the accompanying drawing, forming part thereof.

10 My design consists in a lid or cover of a watch, a portion of the surface of which is made up of different colors or shades of color.

As shown in the accompanying drawing, the central portion or field of the case, cover, or lid of the watch is all one color and left plain, or, if desired, may bear any conventional or well-known design or figure, but which, however, does not constitute a part of my present invention. That portion of the lid or cover lying outside of this central field is made up of different colors or shades of color, and may, if desired, be chased or engraved, thereby blending such colors or shades of color and producing a new, beautiful, and 25 æsthetic effect.

Referring to the accompanying drawing, A represents the central field of the watch-case, of one color and left plain, or, as before stated, carrying any conventional and well-known design. The peripheral portion of 30 the case lying between the central field A and the outer edge of the case is made up of different colors or shades of color, B representing a band, being one of a series of similar bands or stripes contrasting in color or shade of 35 color with that portion represented by C.

D represents still another portion, band, or stripe, contrasting in color or shade of color with those represented by B and C.

What I claim as new, and desire to secure 40 by Letters Patent, is—

The design for a watch-case, as herein shown and described.

Signed at New York, in the county of New York and State of New York, this 20th day of 45 December, 1889.

THOMAS BENFIELD.
